CHAIN ALARM LOCKSET

Felix Gilbert, New York, N.Y., assignor to General
Alarm Corporation, New York, N.Y., a corpora-
tion of Delaware

Filed Oct. 24, 1966, Ser. No. 4,380

Term of patent 14 years

(Cl. D50—5)

FIG. 1 is a front elevational view of a chain alarm lockset embodying my new design;

FIG. 2 is a top plan view of the lockset of FIG. 1;

FIG. 3 is a side elevational view of the lockset of FIGS. 1 and 2;

FIG. 4 is a side elevational view of said lockset; and

FIG. 5 is a cross-sectional view taken horizontally across the face of FIG. 1.

The chain in FIGS. 3 and 4 has been shown broken away for ease of illustration.

I claim:

The ornamental design for a chain alarm lockset, as shown and described.
